A. L. RIKER,
 CONTROLLING MEANS FOR INTERNAL COMBUSTION ENGINES,
 APPLICATION FILED FEB. 10, 1906.
 1,168,421.
 Patented Jan. 18, 1916.

UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

CONTROLLING MEANS FOR INTERNAL-COMBUSTION ENGINES.

1,168,421.

Specification of Letters Patent. Patented Jan. 18, 1916.

Application filed February 10, 1908. Serial No. 300,418.

To all whom it may concern:

Be it known that I, ANDREW L. RIKER, a citizen of the United States, residing at Bridgeport, in the county of Fairfield and State of Connecticut, have invented an Improvement in Controlling Means for Internal-Combustion Engines, of which the following description, in connection with the accompanying drawings, is a specification, like letters on the drawings representing like parts.

My invention relates to controlling means for internal combustion engines, being especially, though not exclusively, adapted, for the control of internal combustion engines, of the type employed upon motor vehicles.

My invention will be best understood by reference to the following description when taken in connection with the accompanying illustration of one specific embodiment thereof, while its scope will be more particularly pointed out in the appended claims.

In the drawings, Figure 1 shows a system of control embodying one form of my invention applied to the partial assemblage of parts upon a motor vehicle; Fig. 2 is a section in elevation taken through the mixing chamber and throttle valve shown in outline in Fig. 1; Fig. 3 is a detail in plan conventionally representing a speed governor attached to the governor rods shown in Fig. 1, and Fig. 4 is a detail of the attachment of the accelerating lever to the actuating rod.

Referring to the drawings and to the specific embodiment of my invention there shown, there is represented an explosion engine A, herein of the four-cylinder type, and provided with a jacket, casing and other usual attached parts, and a steering or controlling post B of the type usually employed in motor vehicles, the engine and controlling post being represented with relation to each other and with reference to the frame of a motor vehicle, which is partially indicated in dotted lines, in the position ordinarily occupied by such parts in motor vehicles of modern construction.

It will of course be understood that, while my invention has peculiar application to the control of a motor vehicle engine and is best described with reference thereto, in certain of its broad features it is equally applicable

to engines employed for other purposes than the propulsion of motor vehicles, and to engines of other types and constructions than the one here represented.

In the disclosed embodiment of my invention the several cylinders are supplied with an explosion mixture of gaseous fuel through branched admission pipes a, a leading from the common upright conduit a' which latter is joined to the outlet opening of a gas-mixing chamber b. The mixing chamber is mounted upon the carburetor c, secured to the side of the engine casing. The carburetor may be of any suitable or usual construction but preferably should be such as is capable of receiving a supply of liquid volatile fuel from a suitable source (not shown), atomizing or otherwise gasifying the same and delivering to the mixing chamber, through the opening b' in the underside thereof, a mixture of the gasified fuel with a suitable quantity of air.

Exit or discharge from the mixing chamber takes place through the port b² at one end of the mixing chamber which opens into the annular chamber b³ having direct communication through the passage b⁴ with the engine admission pipe a'. Passage of the gas through the port b² is controlled by the appropriately formed piston valve d, slidably mounted lengthwise the chamber and acting to open or close the port. The leading edge of the valve is preferably provided with means such as the V-shaped notches shown so that the opening or closing of the exit passage takes place gradually instead of abruptly and a more delicate control at the critical period of final closure thereby obtained.

Any suitable means may be employed for moving the valve, but I prefer to place the same normally under the control of a speed-responsive device so that the quantity of fuel supplied to the engine is varied automatically and in response to the changing speed requirements. Any suitable connections for accomplishing this purpose may be employed, but in the illustrated embodiment of my invention there is provided an actuating rod d' which slides in the head of the mixing chamber and has a threaded end fastening to the valve. The opposite end of the actuating rod is secured by a joint and adjustable turnbuckle to the rod d², the

forked end of which is jointed at d^3 to the laterally extending link d^4 . The latter is pivoted at d^5 upon the engine casing but has interior connections with a centrifugal governor, conventionally represented at d^6 , the latter driven through appropriate gearing from the engine shaft, so that with changes in engine speed the link d^4 is moved about its pivot, causing the throttle valve to be slid

10 in one direction or the other upon its seat.

When the engine is at rest the governor weights draw the throttle valve to the full line position shown in Fig. 2. As soon as the engine reaches normal speed, movement 15 of the governor weights throws the throttle valve approximately to the position represented in dotted lines, from which position it varies to one side or the other according to the engine speed. In the described embodiment of my invention the governor weights, as is usual, act against the restraining 20 effect of one or more springs.

In order to render the acting of the governor adjustable at will during the operation 25 of the engine, thereby to alter the speed to which the governor tends to regulate the same, the springs, or other yieldable elements, against which the governor weights act, are preferably rendered manually adjustable. This adjustment, if desired, might take place at the governor itself, where the principal governor controlling springs are located, but preferably there is provided an additional yielding member, more accessibly 30 located and against which the governor is forced to act, at least during periods of critical control, which spring member may be adjusted and preferably remains easily within the reach of the operator during the 35 running of the vehicle.

Referring to the drawings, there is provided the auxiliary actuating rod e , having a sliding fit in the rear wall of the mixing chamber the forward end of said rod being 40 loosely mounted in the body of the piston valve and opposed to the end of the actuating rod d' , but preferably separated therefrom by a short space when the valve is in its extreme position to the right, as shown 45 in Fig. 2. When the engine starts, the valve moves to the left to partially close the port b^2 without opposition until the end of one rod abuts against the other, when further closing movement can take place only 50 through displacement of the auxiliary actuating rod e . The latter at the rear of, and exterior to, the mixing chamber, has a collar e^2 between which and the adjustable but 55 relatively fixed collar e^3 is a compression spring e^4 which therefore when compressed acts to oppose backward movement of the auxiliary actuating rod e . After the engine has started and the valve is moved to the dotted line position shown in Fig. 2, the 60 spring e^4 may be made to oppose and regu-

late the governor movement to an extent which is dependent upon the degree of spring compression. To render the latter readily adjustable by the operator, the collar e^3 is secured to a link e^5 jointed to a horizontal arm e^6 , the latter fixedly secured to the upper end of a short upright shaft e^7 , journaled in a bracket e^8 , to the lower end of which is secured the segmental bevel gear e^9 . The latter meshes with a similar gear 75 e^{10} upon the extreme lower end of the shaft rod e^{11} , which passes interiorly through the controlling post B for its entire length and is provided at its extreme upper end with an operating arm or handle e^{12} . A segmental ratchet which is partly shown at e^{13} , is fixed upon the end of the controlling post and with this a spring-pressed tooth or pawl (not shown, but of a common form) upon the end of the lever e^{12} engages, so 80 that the latter may be held in any position in which it is moved.

It will be evident that the spring e^4 might be proportioned so as to cause the two rods to abut against each other in all positions 90 of the valve, but I prefer so to construct it that the spring is ineffective to force the actuating rod e beyond some such position as is shown in Fig. 2. The upper end of the controlling post has the steering wheel 95 C, which during the operation of the vehicle is held by the operator, so that the hand lever e^{12} for adjusting the governor controlling spring is immediately accessible and readily adjustable. The ratchet segment e^{13} , however, being fixed, does not turn with the steering wheel and movement 100 of the latter therefore has no effect on the throttle.

A second hand lever f is connected to a 105 sleeve f' within the controlling post, the latter having at its lower end the bevel gear f^2 meshing with the segmental gear f^3 , whereby the upright sleeve f' , also journaled in the bracket e^8 is turned, giving a fore 110 or aft movement to the actuating lever f^6 , which shifts the cam shaft (not shown) for varying the action of the ignition cams and advancing or retarding the time of ignition.

In addition to the governor control over 115 the throttle described, there is also provided additional means for varying the fuel supply or maintaining an increased supply, irrespective of the engine speed, one practical advantage of such a device in connection with a motor vehicle engine being its action as an accelerator temporarily to accelerate the engine speed when the speed afforded through the governor control is lower than desired. For this purpose the 120 actuating rod e has slidably secured to its rear end the cap g which latter is connected to be moved forwardly or backwardly by the yoke-shaped lever g' , pivoted at g^2 and having the rearwardly and downwardly in- 125 130

clined arm g^3 . The lever g' is normally retracted by the spring g^4 so as to bring the cap g against the abutment g^5 upon the controlling post, there being provided in this 5 position of the cap a considerable clearance between the inner wall of the same and the end of the actuating rod so that the latter is free to be moved, without conflict with the cap, in one direction or the other as the 10 throttle valve responds to the control of the governor.

Against the rear upper face of the lever g^3 , however, bears the lower end of the push rod g^6 , against which the operator of the 15 vehicle may press his foot at any desired time, this acting to throw the lever down and the cap forward and against the end of the actuating rod to force the throttle valve open, thereby temporarily assuming control 20 of the throttle and superseding the governor control. In this manner the throttle valve may be forced partially or wholly open against the action of the governor and there maintained as long as desired.

25 In operation the proper adjustment of the governor weights and springs provide regulations for any usual or suitable engine speed. If the operator wishes to increase this speed, either for the instant or for any 30 length of time, he has merely to place the spring e^4 under compression by turning the hand throttle lever e^{12} and by setting said lever to correspond to different degrees of compression of the spring, he can accelerate 35 the action of the engine either slightly or to a very great extent.

Whether the throttle is under the sole control of the governor or under the control of the governor acting in opposition to the 40 spring e^4 , foot pressure upon the accelerator rod g^6 may be employed to force the throttle open and temporarily accelerate the speed and supersede the governor control.

45 While the compression spring e^4 might be placed in other relations to the throttle and its governor, I prefer to place it upon some such part as the rod e between which and the throttle there is some degree of lost motion. When the engine speeds up and the 50 governor weights fly out, they tend to cause the throttle valve to overthrow its true position. If there is a slight compression placed upon the spring e^4 , however, it tends to cushion the movement of the valve toward 55 its close and prevent the overthrow thereof.

During the operation of the engine air charged with the gaseous vapor is constantly available for the mixing chamber from the underlying carburetor in an amount proportioned to the demands of the engine. This 60 mixture, however, ordinarily requires to be diluted with a further mixture of air. To permit this, there is provided means for automatically admitting to the mixing chamber a quantity of air proportioned to the re-

quirements and running conditions of the engine. For this purpose there is provided an air admission chamber h in the casing K , the latter secured to the top of the casting in which is formed the mixing chamber, there 70 being free communication between the latter and the admission chamber h . The top of the casing has a cap h' threaded therein and having a central opening which may be closed by the plate valve h^2 , the latter engaging a seat formed on the lower side of the cap. The valve is provided with a stem h^4 , slideable in the bearing h^4 , which is carried by a spider formed upon the cap. The valve 75 is normally held to its seat by the spring h^5 80 acting against the washer h^6 , which is adjustably secured to the valve spindle. On decrease of pressure within the casing K the valve h^2 tends to open and admit the necessary supply of air, maintaining such supply 85 so long as is requisite. The amount of auxiliary air needed will be greater as the engine speed increases, but inasmuch as increase or decrease in engine speed is followed by increase or decrease in the suction created by 90 the engine piston, this suction acting within the air admission chamber h upon the lower side of the plate valve, will tend to position the latter according to the speed of the 95 engine.

While I have shown and described in detail one embodiment of my invention, it is to be understood that the same is not limited to the details disclosed or the form and relative arrangement of parts, or to the particular application of the invention herein set forth, but that many modifications and departures therefrom may be made without deviating from the spirit of the invention.

I claim—

1. An internal combustion engine having a fuel chamber, a throttle valve in said chamber, a controlling member secured to said valve and passing through one end of said chamber, a speed governor connected with said controlling member, a second controlling member operatively related to said valve and passing through the opposite end of said chamber, an adjustable spring 110 operatively related to said second member and opposing the movement of said valve by said governor, and an accelerating device also operatively related to said second member for temporarily controlling said valve to the exclusion of said governor. 115

2. An internal combustion engine having a gas chamber, a piston throttle valve slideable in said chamber, a rod secured to one end of said valve and through which the valve may be moved to control the fuel supply to the engine, a governor connected to said controlling rod, a second rod operatively related to said valve but extending through said chamber in the opposite direction, an adjustable spring for acting upon 125 130

- said second rod to cause the latter to oppose governor controlled movement of the valve, and an accelerator operatively disconnected from said second rod but adapted 5 to be moved at will to control the same and move the throttle to supersede the governor control thereof.
3. An internal combustion engine having a carburetor, a mixing chamber adjacent thereto, a piston throttle valve in said chamber, a rod connected to said valve to move the same and control the fuel supply to the engine, a governor connected to said rod, an auxiliary actuating rod also operatively 10 related to said valve and extending in the opposite direction and controlling means connected to said auxiliary actuating rod temporarily to control the valve to the exclusion of the governor.
- 15 4. An internal combustion engine having a gas chamber, a piston throttle valve slidably mounted in the same, a rod secured to said valve, a governor connected to said rod to move the valve, and an auxiliary actuating rod between which and the valve there is provision for relative movement, 20 said rod being adapted to engage the valve when the latter is moved to throttle the mixture.
- 25 5. An internal combustion engine having a carburetor, a mixing chamber adjacent thereto, a throttle valve in said chamber, a governor-controlled actuating rod connected to said throttle valve and passing out of 30 one end of said mixing chamber, an auxiliary actuating rod operatively related to said valve and passing through the opposite end of said chamber, an adjustable spring for acting upon said auxiliary rod 35 to cause the latter to oppose governor-controlled movement of the valve, and an accelerating device normally disconnected from the rod but adapted to be moved to control the same and supersede the governor 40 control of the throttle valve.
- 45 6. A regulating mechanism for an internal combustion engine comprising a throttle valve, a speed governor for controlling the same, and means for changing the controlling adjustment of the governor, said 50 means comprising an auxiliary spring, an arm connected to vary the adjustment of said spring, an upright sleeve member mounted to move said arm, a manually adjustable member, and gearing connection 55 between said upright member and said manually adjustable member.
- 60 7. An internal combustion engine having a fuel chamber, a piston throttle valve mounted to control exit from said chamber, a controlling rod secured to one end of said valve, a speed governor connected to said rod and an auxiliary controlling rod extending in the opposite direction, said auxiliary 65 controlling rod being operatively de-
- tached from said valve when the engine is at rest, but adapted to be moved to control said valve.
8. An internal combustion engine having a throttle valve, a speed governor connected to said throttle valve, an auxiliary controlling rod independently controlling said valve, a spring adapted to act upon said rod in opposition to said governor, means for tensioning said spring, and an accelerating member connected to said rod to move the same against the action of the governor. 70
9. The combination with an internal combustion engine, of a throttle valve, a speed governor, connections between said governor and said valve, a valve controlling member having an independent connection to said valve, yieldable means adapted to press said controlling member in opposition to the governor-actuated movement of the valve, means for adjusting the action of said yieldable means, and means adapted to engage the controlling member positively to move the same temporarily to supersede the 80 control of the governor. 85
10. The combination with an internal combustion engine, of a throttle valve, a speed governor connected to move the same, means adapted yieldably to oppose the governor-actuated closing movement of the valve, and a connection providing for lost motion to permit closing movement of the valve prior to the opposing action of the yieldable means. 90
- 100 11. The combination with an internal combustion engine, of a throttle valve, a speed governor connected to move the same, and an actuating member for moving the valve in opposition to the governor-actuated closing movement to supersede the governor control; said actuating member having a connection providing for lost motion to permit governor-actuated opening movement of the valve without movement of said actuating member. 105
- 110 12. A regulating device for an internal combustion engine comprising a throttle valve, a speed governor for controlling the same, and means for changing the controlling adjustment of the governor, said means comprising an auxiliary spring, a member connected to vary the adjustment of said spring, a manually adjustable member for moving said spring-adjusting member and 115 a gearing between the manually adjustable member and the spring-adjusting member. 120
13. The combination with an internal combustion engine of a throttle valve, a speed governor connected to the valve, a valve controlling member having an independent connection to the valve, yieldable means adapted to press said valve controlling member in opposition to the governor-actuated movement of the valve, means for 125 130

regulating the pressure of said yieldable means, and an accelerating member adapted to engage the controlling member positively to move the same temporarily to supersede 5 the control of the governor.

14. An internal combustion engine having a gas chamber, a throttle valve controlling the flow of gas from said chamber, a rod connected to said valve to move the 10 same and control the fuel supply to the engine, a governor connected to said rod, an auxiliary actuating rod also operatively related to, but disconnected from, said valve, and controlling means connected to said 15 auxiliary actuating rod temporarily to control the valve to the exclusion of the governor.

15. A regulating mechanism for an internal combustion engine comprising a 20 throttle valve, a speed governor for controlling the same, and means for changing the controlling adjustment of the governor, said means comprising an auxiliary spring, and a member connected to vary the adjustment of said spring, said member having lost motion connection with said valve permitting the latter to be opened by said governor independently of the adjustment of 25 said member.

30 16. A regulating mechanism for an in-

ternal combustion engine comprising a throttle valve, a speed governor for controlling the same, and means for changing the controlling adjustment of the governor, said means including a yielding device, a 35 member connected to vary the adjustment of said yielding device, and a lost motion device permitting said governor to open said valve independently of the action of said yielding device in any position of said member.

17. The combination with an internal combustion engine, of a throttle valve, speed-responsive means connected to move the same, and an actuating member, for moving the valve in opposition to the speed-responsive closing movement to supersede the speed-responsive control, said actuating member having a connection providing for lost motion to permit speed-responsive opening movement of the valve without movement of said actuating member in any position of the latter.

In testimony whereof, I have signed my name to this specification, in the presence of 50 two subscribing witnesses.

ANDREW L. RIKER.
